VACUUM FEEDING DEVICE.

1,289,790.

Specification of Letters Patent.

Patented Dec. 31, 1918.

Application filed November 8, 1917. Serial No. 200,927.

To all whom it may concern:

Be it known that I, JACOB JACOBSEN, a citizen of the United States, residing at the city and county of San Francisco and State of California, have invented new and useful Improvements in Vacuum Feeding Devices, of which the following is a specification.

This invention relates to a vacuum feeding device for internal combustion engines, and particularly to a vacuum or suction-actuated, automatic pump for transferring gasolene from a tank or reservoir located below the carburetor of the engine to an auxiliary elevated tank, from which the gasolene may flow by gravity to the bowl of the carburetor.

One of the objects of the present invention is to provide a novel form of automatic valve mechanism; to increase the storage capacity of the auxiliary tank; to simplify the mechanism without sacrificing the certainty of the operation; and also to improve other features which will hereinafter be described.

25 The invention consists of the parts and the construction and combination of parts as hereinafter more fully described and claimed, having reference to the accompanying drawing, in which—

30 Figure 1 is a central, vertical, longitudinal section through the device.

Fig. 2 is a plan view of same.

Fig. 3 is a diagrammatic view, showing the application of the invention.

35 Referring to the drawings in detail, A indicates the automatic fuel-feeding device, 2 an internal combustion engine, 3 the intake manifold, 4 the bowl of the carburetor, and 5 the main gasolene supply tank. This 40 tank is generally located below the bowl of the carburetor, and it is the purpose of this invention to provide means for automatically transferring gasolene from the main tank 5 to the auxiliary tank A through a pipe 6 and to permit the gasolene to flow by gravity from the tank A to the bowl of the carburetor through a pipe 7.

45 The device shown consists of a main tank A and an interior tank or container B, these tanks being secured together by means of a head or cover plate 8, as shown. The inner tank is provided with a bottom 9, to which is attached a discharge pipe 10, in the lower end of which is mounted an automatic check

valve 11. The main tank is also provided with a bottom member 12, to which the gravity discharging fuel pipe 7 is connected, the pipe 7 being extended upwardly within the tank, as shown at 13, to form a trap which will always maintain a fuel level above the valve 11.

50 Formed in the head 8 are three extensions, such as shown at 14, 15 and 16. These extensions are externally threaded to receive pipe unions 17 to permit a simple attachment of the pipes 6, 18 and 19, as shown. The pipe 18 is connected with the intake manifold 3 of the engine while the pipe 19 is extended upwardly to serve the function of a vent, as will hereinafter be described. 55 The pipe 6 is extended downwardly within the tank B to deliver the gasolene elevated from the tank 5 at a point where it will not disturb the action of a float shown at 20.

55 This float 20 is provided with an upwardly extending valve stem 21, the upper end of which is pointed to engage a seat 22. The lower end of the float is provided with a guide rod 23 which enters the lower discharge pipe 10 and is guided with relation 60 thereto by means of a bearing bracket 24. The valve stem 21 and the lower projecting rod 23 form a perfect guide for the float and only permit a vertical movement of same.

65 Extending through the connection 16 is a valve stem 25 which is guided at its upper end in the head, as shown at 26, and at its lower end by a bracket 27. The upper end of the rod is provided with a valve head 28 which is adapted to be raised or lowered 70 with relation to a seat 29. The connection 16 is also provided with a lateral venting 75 passage 30 which communicates with an annular chamber 31 formed between the tanks A and B and with the vent pipe 19. 80

85 The construction and position of the lower check valve 11 form one of the important features of the present invention. This check valve is positioned directly below and in alinement with the pipe 10 and is supported in this position by a guide bracket 11^a secured on the lower end of the pipe. A seat is also formed on the lower end of the pipe 10 for the reception of the valve and as 90 only a comparatively small movement is required, it can readily be seen that this valve 95 will quickly open or close to permit fuel admitted to the inner tank to discharge into 100

the main tank and vice versa to quickly close the moment the inner tank is subjected to vacuum, thereby preventing fuel already admitted to the main tank from 5 turning or backing up into the main tank.

The operation will be substantially as follows:

With the engine operating, it can readily be seen that a suction or partial vacuum 10 will be produced in the inner chamber or tank B. This will, of course, cause gasolene to be drawn up from tank 5 through pipe 6 and delivered to the inner tank B. The suction produced also causes the check valve 15 11 to close and thereby prevents the gasolene or fuel admitted from discharging into the main tank A. The float valve under such conditions reaches its lowermost position and permits the venting valve 28 to remain on its seat and thereby prevents outside air from entering. Continued suction and admission of fuel to the inner tank causes the float 20 to gradually rise in proportion to the increase in fuel level, and a point is finally reached where the valve 21 25 will engage the seat 22 and close off the suction connection. The valve 28 is simultaneously lifted from its seat as the upper end of the float engages the stem 25 and air is then admitted through the vent pipe, thereby 30 breaking the vacuum and permitting the check valve 11 to open and the fuel collected in the tank B to discharge into the main tank A.

The float remains in its uppermost position until the fuel level in the tank B has receded a considerable distance; that is, it might be stated that valve 21 adheres to the seat 22 due to the constant suction in the 40 pipe 18. The weight of the float is, however, sufficient to pull the valve away from the seat the moment the fuel level has receded a certain distance and it, therefore, pulls away quickly the moment this point 45 is reached. Valve 28 is simultaneously permitted to seat as the recession of the float allows said valve to drop. Suction is again produced in the inner tank B and valve 11 is, of course, automatically closed, thereby 50 preventing the fuel already delivered in the main tank from returning or backing up into the inner tank. The lateral venting passage, which is in constant communication with the pipe 19, maintains atmospheric 55 pressure in the main tank A, thereby permitting the fuel delivered thereto to run by gravity through pipe 7 directly to the bowl of the carburetor, while the vent connection formed between the inner tank and the pipe 60 19 is intermittently opened and closed, it being closed while fuel is being admitted and opened during the time period when the fuel is transmitted through the pipe 10 to the main tank.

65 The structure as a whole is very simple

and compact in arrangement. There are, practically speaking, only three moving parts, to-wit, the valve 28, the float 20 and the check valve 11, and as these are as elementary and simple in construction and arrangement as it is possible to produce any mechanical element, it is obvious that certainty of operation can always be relied on. The manner of securing the inner tank to the outer tank and in turn the two tanks to 75 the head 8 is also of importance as it reduces the cost of manufacture materially.

The device as a whole does not only serve the function of an elevated auxiliary reservoir for fuel, but it also acts as a pump for 80 transferring fuel from the source of supply thereto, and as its action is positively automatic it can readily be seen that its application and use as here shown are of considerable importance.

85 The materials and finish of the several parts of the device may be such as the experience and judgment of the manufacturer may dictate.

I wish it understood that various changes 90 in form, proportions, and minor details of construction may be resorted to within the scope of the appended claims and that I do not wish to limit myself to the specific design and construction here shown.

95 Having thus described my invention, what I claim and desire to secure by Letters Patent is—

1. A vacuum feeding device comprising an inner and an outer tank, a head member 100 adapted to form a closure for the inner and outer tanks and to separate said tanks one from the other, a discharge pipe secured in the lower end of the inner tank forming a communication between said tanks, a check 105 valve on the lower end of said pipe, a discharge pipe on the lower end of the outer tank and extending up thereinto above the check valve whereby to provide a liquid trap thereabout; a feeding pipe connected 110 with the upper end of the inner tank, a suction pipe connected with the upper end of the inner tank, a venting pipe connected with the upper end of the inner and outer tank, a float within the inner tank, a stem 115 on each end of the float, guides for said stems securing the float against lateral displacement but permitting it to move freely vertically, a valve member on the upper stem section, a valve seat in the suction pipe 120 with which said valve is engageable, a valve adapted to close the venting opening in the head communicating with the inner tank, a stem projecting downwardly into the inner tank adapted to be engaged by the float and 125 a passage in the head connecting the interior of the outer tank with the venting pipe.

2. A vacuum feeding device comprising an outer tank having its upper edge turned inwardly, an inner tank having its upper 130

- edge turned outwardly over the inturned edge of the outer tank for being supported thereby, a head secured to the upper edges of the tanks and provided with a venting opening communicating with the outer tank, a second opening for connection with the intake manifold and a third opening for connection with a liquid supply, a valve controlled passage between the two tanks, an outlet leading from the outer tank, a valved communication between the venting opening and the inner tank, a float in the inner tank, a stem extending upwardly from the float and through the second opening of the head formed on its upper end with a valve, and a removable valve seat secured to the head over the second opening for engagement by the valve end of the stem.
3. A vacuum feeding device, comprising a pair of tanks mounted one within the other, means for producing a suction in the inner tank, means connecting the inner tank with a source of liquid supply, means for venting the inner tank, a float within the inner tank, a slidably mounted valve adapted to open or close the vent connection, a valve attached to the float adapted to open or close the suction connection, a stem on the venting valve adapted to be engaged by the float and lifted thereby to open the venting connection, a discharge pipe connecting the inner tank with the outer tank, a vertically movable check valve mounted directly below the discharge pipe in alignment therewith for seating thereon, and a bracket carried by the discharge pipe for guiding the check valve to its seat.
4. The combination with the discharge pipe forming a communication between the inner and outer tanks in the device de-
- scribed, of a bearing bracket secured on the lower end of the pipe, a valve seat on the lower end of the pipe across which the bracket extends in spaced relation to the seat, a valve adapted to engage said seat, and a vertically positioned stem to which said valve is secured slidably mounted in the bearing bracket.
5. The combination with the inner and outer tanks described, of a head member adapted to form a closure for the inner and outer tanks and to separate said tanks one from the other, a discharge pipe in the lower end of the inner tank forming a communication between said tanks, a check valve on the lower end of said pipe, a float within the inner tank, a guide rod on each end of the float, a valve member formed on the upper end of one of said rods, a seat in the head with which said valve is adapted to engage, an extension formed on the head, a vent pipe connected with said extension, a central opening formed in said extension communicating with the inner tank, a lateral opening in said extension communicating with the interior of the outer tank, a valve seat in the central opening, a valve adapted to engage said seat, a stem on said valve projecting downwardly into the inner tank, said valve adapted to be raised and lowered from its seat by engagement of the float with the rod, and a bearing bracket for the rod.
- In testimony whereof I have hereunto set my hand in the presence of two subscribing witnesses.

JACOB JACOBSEN.
